(No Model.)

F. R. WOLFINGER.

WINDOW SASH.

No. 288,751.

Patented Nov. 20, 1883.

UNITED STATES PATENT OFFICE.

FRANCIS R. WOLFINGER, OF CHICAGO, ILLINOIS.

WINDOW-SASH.

SPECIFICATION forming part of Letters Patent No. 288,751, dated November 20, 1883.

Application filed June 19, 1883. (No model.)

To all whom it may concern:

Be it known that I, FRANCIS RUDOLPH WOLFINGER, of Chicago, in the county of Cook and State of Illinois, have invented a new and useful Improvement in Window-Sashes; and I do hereby declare that the following is a full and exact description of the same, reference being had to the accompanying drawings, and to the letters of reference marked thereon.

10 Figure 1 is an elevation of the inside of a window-frame, showing my improvement applied to the two sashes. Fig. 2 is a section, taken horizontally through Fig. 1 in the plane indicated by the dotted line x x thereon, showing the two sashes swung inward, the upper sash being depressed to its fullest extent and the lower sash being raised. Fig. 3 is a perspective detail view of a sectional sash-stile with its dowel-pins. Fig. 4 is a perspective 15 view of one of the hinged or pivoted sashes and its sectional stile.

The object of this invention is to afford easy access to the outside surfaces of glass in window-sashes for the purpose of cleaning the same; and the nature of my invention consists in certain novel improvements whereby I practically carry into effect the above object in a very simple manner, as will be fully understood from the following description, when 20 taken in connection with the annexed drawings.

Before particularly describing my improvements I will state that I may or may not hinge one side of each sash to a stile or upright slide; but I prefer to do so for the reason that the sash will be connected to the window-frame, and can be readily swung inwardly for the purpose of cleaning the outer side of the glass.

25 A designates a window-frame, which may be constructed in the usual well-known manner, and which is preferably constructed with boxes to receive weights and cords for balancing the sashes in the usual way.

B B designate the balancing weights; a a, the suspension cords, and b b the pulleys.

30 C C designate the frames of two window-sashes, each of which may be provided with one or more glasses. The meeting rails of these sashes are beveled in the usual manner, so that when they are brought together a close joint will be formed. Each sash-frame is

preferably hinged on one side, as at d, to a stile, D, and when it is closed it is connected by dowel-pins e to another stile, D'. The two stiles D D' of each sash have attached to them the weighted cords a a, and these stiles are rabbeted to form close joints with the corresponding rabbeted edges of the sash-frame. Both stiles D D' of each sash are provided with lips e e, which are received into 55 grooves made in the window-frame strips E E, thus forming guides and keeping the said stiles in their places in the window-frame, whether the sash be opened or shut.

I have represented in the annexed drawings 60 a window-frame having two sashes, both of which are hinged to their stiles D; but I may pivot the sashes to their stiles or employ hidden hinges; or I may omit the hinges and substitute pins or other suitable catches for uniting the sashes to their stiles. 70

It will be observed that I have combined with a window-sash frame two stiles, D D', to which this frame is attached, so that free access is allowed to the outside of the glass for the 75 purpose of cleaning it without the necessity of removing the window-strips or exposing a person to the danger of climbing on the outside of a window. It will also be observed that I provide a pin, g, for the purpose of connecting one side of each sash to its stile D'. I also provide a high soffit, H, at the top of the frame A, inside thereof, for the purpose of allowing the inner sash to be raised high enough to swing the outer sash into the room 80 when it is lowered to the bottom of the frame A.

One very essential feature of my improvement is the manner of rabbeting the sash-frames to the stiles, and rigidly connecting the said frames and stiles by means of the 85 dowel-pins e and the key-pins g, whereby there is no possibility of a casual displacement of the parts, and close joints are formed.

Another important feature of my invention is the guide and retaining lips e e on stiles, 90 which are received in grooves made in the window-strips, thus, as above stated, keeping the stiles in their places in the window-frame.

It will be observed by reference to Fig. 100 that the vertical edges of the frames c are beveled and fit so tightly that they keep out wind and water.

Having described my invention, what I claim as new, and desire to secure by Letters Patent, is—

1. The combination of rabbeted stiles, a window-sash fitted thereto, the dowel-connections of the stiles and sash, and the retaining-pins *g*, all constructed and adapted to operate substantially in the manner and for the purposes described.
- 10 2. The combination of the rabbeted stiles *D D'*, having a window-sash attached to them, the dowel-pins *c c*, the retaining-pin *g*, the lips *e e*, and the grooved strips *F*, all construct-

ed and adapted to operate substantially in the manner and for the purposes described.

- 15 3. The combination of the soffit *H*, at the top of the frame *A*, with the window-sash, and the stiles *D D'*, applied to the window-frame, substantially as and for the purposes described.

20 In testimony whereof I affix my signature in presence of two witnesses.

FRANCIS RUDOLPH WOLFINGER.
